EDWARD POOLE, OF PHILADELPHIA, PENNSYLVANIA, ASSIGNOR TO THE

DESIGN FOR CARPET.

SPECIFICATION forming part of Design No. 26,920, dated April 13, 1897.

Application filed December 26, 1896. Serial No. 617,099. Term of patent 31 years.

To all whom it may concern:

Be it known that I, EDWARD POOLE, a subject of the Queen of Great Britain, residing at Philadelphia, county of Philadelphia, and State of Pennsylvania, have invented and produced a new and original Design for Carpet Fabrics, of which the following is a full, clear, and exact description, reference being had to the accompanying drawing, which forms a part of this specification.

My design as shown in the drawing consists of a new design for the body and border of a carpet fabric.

A represents the body, and B the border. With the exception of the irregular plain portion at the outer edge of the border both body and border are destitute of any pronounced background, and the same general effect runs through both. The body is divided by scroll and other ornamental work into irregular fields, each of a prevailing color and relieved by flowery and other ornamentations. The different fields are indistinctly separated, and variously shaped and colored flowers and

figures of curving and angular contour are interspersed over the whole body, merging into and with the obscurely-defined fields aforesaid. The border is similar in appearance to a portion of the body, having a central field with flowery and other ornamentations indistinctly divided by scroll and other work from a surrounding field having a general flowery effect.

Having now fully described my invention, what I claim, and desire to secure by Letters Patent, is—

1. In a design for a carpet fabric, the body A substantially as shown.
2. In a design for a carpet fabric, the border B substantially as shown.
3. The design for a carpet fabric comprising the body A and the border B.

In testimony of which invention I have hereunto set my hand.

EDWARD POOLE.
